UNITED STATES PATENT OFFICE.

SAMUEL MILLER, OF NEW YORK, N. Y.

DESIGN FOR A TEXTILE FABRIC.

Application filed September 15, 1928. Serial No. 28,160. Term of patent 3½ years.

To all whom it may concern:

Be it known that I, SAMUEL MILLER, a citizen of the United States, residing at New York, in the county of New York and State of New York, have invented a new, original, and ornamental Design for a Textile Fabric, of which the following is a specification, reference being had to the accompanying drawing, forming part thereof.

The figure of the drawing is a plan view of a unit of my new design, with extensions of the repeat units on the four sides by dotted lines.

I claim:

The ornamental design for a textile fabric as shown.

SAMUEL MILLER.
